C. L. REED,

MIXER,

APPLICATION FILED JUNE 17, 1918.

1,300,015.

Patented Apr. 8, 1919

UNITED STATES PATENT OFFICE.

CHARLES L. REED, OF ROCHESTER, NEW YORK.

MIXED.

1,300,015.

Specification of Letters Patent.

Patented Apr. 8, 1919.

Application filed June 17, 1918. Serial No. 240,476.

To all whom it may concern:

Be it known that I, CHARLES L. REED, a citizen of the United States, and resident of Rochester, in the county of Monroe and 5 State of New York, have invented certain new and useful Improvements in Mixers, of which the following is a specification.

The present invention relates to internal combustion engines and more particularly to 10 the means for supplying fuel to such engines, an object of this invention being to provide means which will act on the fuel as the latter is discharged by the manifold into the valve chamber to effect an efficient 15 mixture of the fuel. Another object of the invention is to produce a whirling action of the fuel as the latter enters the valve chamber, so that the unmixed liquid fuel will be distributed over a wide area on one of the 20 walls of the valve chamber and in this way will be more readily and effectively vaporized.

To these and other ends the invention consists of certain parts and combinations of 25 parts all of which will be hereinafter described, the novel features being pointed out in the appended claims.

In the drawings:

Figure 1 is a view of the manifold of a 30 gas engine used in the "Ford" automobile, the mixing device being shown in position in the two outlets of the manifold;

Fig. 2 is a fragmentary view of a "Ford" engine casing and a portion of the manifold 35 showing the mixing device partially in section; and

Fig. 3 is a fragmentary sectional view of the manifold and the engine casing showing the mixer in side elevation.

In the Ford engine the fuel passes from 40 the carburetor (not shown) into a manifold 1 which conducts it by two branches to two valve chambers 2 formed in a casing in which the cylinders are also formed. Each 45 valve chamber has an opening 3 directly opposite a wall 4 between the two valves (not shown) operating in the openings 5. As the fuel enters the chamber through the opening 3 it impinges the wall 4, and any unvaporized fuel collects on the wall to be vaporized 50 by the heat of said wall or by the fuel passing over said wall. In many instances the fuel is too rich with unvaporized fuel and as a consequence the latter accumulates to

such an extent that it is drawn unvaporized 55 within the cylinders.

According to this invention, the fuel, as it enters the valve chamber 2, is given a whirling action which spreads the fuel over a greater area of the wall 4 than is possible 60 without this whirling action, and as a consequence the unvaporized fuel does not accumulate at one point, so that it is possible to vaporize the fuel more easily and effectively.

This mixing device, in this instance, utilizes as its support the usual ring 6 which fits within the manifold and the opening of the valve chamber, and it comprises a plurality of blades 7 having a slight spiral or 70 screw form and secured together each along one edge on a line axially of the ring, said blades being rigidly secured to the ring at their outer edges, and each gradually decreasing in width toward one end by curving 75 their outer edges toward the axial line. It is well recognized that the unvaporized fuel travels at the center of the fuel column while the vaporized fuel is outermost. The mixer by being formed as described has the most 80 effective portions at the center, so that the unvaporized fuel is influenced most strongly by the blades and is whirled over the face of the wall 4, while the vaporized fuel has a substantially free path owing to the spaces 8.85 between the blades.

What I claim as my invention and desire to secure by Letters Patent is:

1. In combination with a manifold of a gas engine, a mixer arranged in the manifold and having stationary blades extending outwardly from a line axially of the flow of material through the manifold, said blades gradually decreasing in width from the axial line to their outer edges and being twisted 90 spirally, the outer edges of the blades being separated so that fuel passing the mixer adjacent the outer edges does not impinge the blades and does not have the direction of its travel changed, and the twisted portions of 95 the blades acting to throw outwardly a portion of the fuel column into the non-deflected portion, thus producing a mixture of the column without any material retardation of such column.

2. In combination with a manifold of a gas engine, a mixer having stationary blades so formed as to permit the free passage with-

out deflection of the outer portion of the column of fuel passing through the manifold, and to whirl an inner portion of the column outwardly into the outer portion of the column.

3. A mixing device comprising a ring and a plurality of screw blades rigid with and projecting from the ring secured to each

other throughout their lengths, and each gradually decreasing in its width toward the end of such blade.

4. A mixing device comprising a plurality of nonmoving twisted blades secured to each other in an axial line, and each gradually decreasing in width toward one end.

CHARLES L. REED.
